UNITED STATES PATENT OFFICE.

REED J. CLARK, JR., OF YOUNGSTOWN, OHIO.

WASHING-MACHINE.

1,285,943.

Specification of Letters Patent. Patented Nov. 26, 1918.

Application filed August 7, 1918. Serial No. 248,789.

To all whom it may concern:

Be it known that I REED J. CLARK, Jr., a citizen of the United States, residing at Youngstown, in the county of Mahoning, 5 State of Ohio, have invented a new and useful Washing-Machine; and I do hereby declare the following to be a full, clear, and exact description of the invention, such as will enable others skilled in the art to which 10 it appertains to make and use the same.

The present invention relates to certain new and useful improvements in washing machines, and has for its object to provide a device of this character which embodies 15 novel features of construction whereby clothes can be thoroughly and quickly cleansed by mechanical means without injury to even delicate fabrics.

Further objects of the invention are to 20 provide a washing machine which is quick and thorough in its action and will enable large quantities of soiled clothes to be washed in a short period of time, which can be operated without difficulty, and which 25 has no delicate parts which are liable to break or get out of repair.

With these and other objects in view, the invention consists in certain novel combinations and arrangements of the parts as 30 will more fully appear as the description proceeds, the novel features thereof being pointed out in the appended claims.

For a full understanding of the invention, reference is to be had to the following description and accompanying drawings, in 35 which:—

Figure 1 is a side elevation of a washing machine constructed in accordance with the invention.

Fig. 2 is a transverse, vertical sectional view through the same.

Fig. 3 is a vertical sectional view taken on a line at right angles to that of Fig. 2.

Fig. 4 is an enlarged sectional view 45 through the rolling weight.

Figs. 5 and 6 are detail views of the packing and clamping means between the two sections of the hollow outer casing.

Corresponding and like parts are referred 50 to in the following description and indicated in all the views of the drawings by the same reference characters.

Referring to the drawings, which illustrate one embodiment of the invention, the 55 numerals 1 and 2 designate the two comple-

mental halves of the hollow outer casing A of the washing machine, said casing having the general shape of a flattened sphere so that a cross section taken in one direction is circular, as indicated by Fig. 3, while a cross section taken at right angles thereto is substantially elliptical, as indicated by Fig. 2. The lower half 1 of the casing A is larger than the upper half and is hollow or partially filled with hot soapy water into which the clothes to be washed are placed preparatory to placing the upper section 2 of the casing in position. Trunnions 3 project from the flattened sides of the lower section 1 of the casing and are axially arranged with respect to the casing, said trunnions being journaled in the upright standards 4 of a supporting frame B. One of the trunnions is shown as having a crank handle 5 applied thereto, while the other trunnion is 75 provided with a pulley 6 by means of which power can be applied thereto if desired.

The meeting edges of the upper and lower sections 1 and 2 of the outer casing are provided with corresponding outstanding flanges 7, one of the flanges being provided with an annular packing ring 8 of rubber or like material which is substantially triangular in cross section and has the base thereof dove-tailed at 9 into the flange, while the 85 V-shaped edge of the packing ring projects outwardly from the flange and is adapted to be seated in a correspondingly shaped groove 10 in the other flange. Positioning pins 11 project from one of the flanges 7 90 and pass loosely through openings in the other flange, said pins serving to hold the casing sections in proper relative position preparatory to tightening the clamps. The flange 7 of the lower casing section 1 is provided with a series of clamping hooks 12 which are adapted to extend around the flange 7 of the upper casing section, said clamping hooks being pivotally connected at 13 to levers 14 which are in turn pivotally connected at 15 to the flange 7 of the lower section 1. These operating levers 14 have a cam action in connection with the clamping hooks 12 and draw the same forcibly into operative position when the levers are 105 swung downwardly against the sides of the casing, although when the levers are swung upwardly the clamping hooks are released. By means of these clamping hooks the two casing sections can be securely locked to 110

gether and a water-tight joint obtained so that the casing A can be turned about its axis without danger of leakage.

The interior of the outer casing A is provided with an annular raceway which is concentric with the axis upon which the casing is pivoted. This raceway is substantially semicircular in cross section, as indicated by Fig. 2, and is provided with transverse corrugations 30 upon which the clothes are rubbed by a rolling weight C which is loosely mounted within the casing and travels around the annular raceway when the casing is rotated about its axis. As this weight rolls over the clothes, the rolling being brought about by the action of gravity as the casing is revolved, the clothes are effectively rubbed against the corrugated walls of the annular raceway and at the same time subjected to a pressure which tends to force or pump the soapy water through the fabric and remove the dirt therefrom. The rolling weight C in its specific construction includes a heavy center 16 which is preferably formed of concrete or some plastic material, and a foraminous shell 17 which completely houses the concrete body and is spaced therefrom, thereby providing a chamber E between the concrete body and the foraminous shell into which the water squeezed or pressed from the clothes directly under the weight can enter, thereby producing a most effective pumping action or circulation of the water through the fabric and causing the fabric to be cleansed without any injurious twisting or rubbing. The foraminous shell 17 is preferably covered by a soft protective layer 18 of rubber or like material, said rubber having a roughened or ribbed outer surface, and being provided with perforations which correspond to and register with the perforations of the foraminous shell. Tubular rivets 19 pass through these corresponding perforations and serve to secure the protective rubber layer 18 to the shell, thereby providing for securing the rubber layer in position without interfering with the passages between the chamber E and the exterior of the rolling weight. The shell 17 is preferably formed in semi-spherical sections which are assembled upon the concrete weight 16 from opposite sides thereof, the meeting edges of the sections of the shell overlapping each other at 20. These overlapping edges 20 of the shell are provided with corresponding openings which are engaged by spring plungers 21 mounted in casings 22 which are embedded in short arms 23 projecting from the concrete weight 16. By pressing the spring plungers inwardly with a nail or suitable instrument, they can be disengaged from the overlapping edges of the foraminous shell and the latter released. The curved ends of the shell sections are pref-

erably engaged by screws 24 which have a threaded engagement with a socket 25 in short arms 26 projecting from the concrete weight. These screws 24 coöperate with the spring plungers 21 to hold the shell sections in position, and by first removing the screws, and then pressing the plungers inwardly the sections of the shell can be released and removed from the concrete weight.

In the operation of the washing machine the casing A is rotated to bring the lower section 1 thereof into an upright position, in which position it may be temporarily locked by some suitable latch means such as an arm 27 which is pivotally mounted upon the supporting frame B and can be swung into engagement with a socket 28 on one side of the casing section. The upper casing section 2 is then removed and the desired quantity of hot soapy water poured into the lower casing section. The clothes to be washed are then inserted in the machine and the ball C lowered into position on top of the clothes. Any large fabric pieces, such as sheets, which might have a tendency to wind themselves around the weighted ball C may be loosely tied into a bundle preparatory to inserting them into the machine. The upper casing section 2 is next tightly clamped in position, after which it is merely necessary to rotate the casing in order to subject the clothes to the action of the rolling weight C and thoroughly cleanse the same. The action of gravity causes the weight C to travel around the annular raceway of the casing as the casing is revolved, and the clothes are thereby rubbed between the corrugated walls 30 of the raceway and the rough or ribbed rubber covering of the weight. At the same time the clothes are subjected to a squeezing action as the weight rolls over the same, said squeezing action being facilitated by the foraminous shell which surrounds the concrete weight 16 and is spaced therefrom, the water which is squeezed from the fabric tending to pass through the perforations of the foraminous shell and to enter the chamber E which is provided between the foraminous shell and the concrete weight. The only surfaces which are directly engaged by the clothes are the corrugated interior walls of the outer casing A and the rubber covering of the rolling weight C, and it will be obvious that even delicate fabrics can be thoroughly washed without danger of injury, since the rubbing and squeezing action of the weight is not violent, although very effective.

Having thus described the invention, what I claim as new and desire to secure by Letters Patent, is:—

1. A washing machine including a hollow casing mounted to rotate about an axis and

provided with an interior annular raceway, a rolling weight loosely mounted within the casing to roll on the raceway as the casing is revolved, and a perforate shell surrounding the weight and spaced therefrom.

2. A washing machine including a hollow casing mounted to rotate about an axis and provided with an interior annular raceway which is substantially semicircular in cross section, a weight loose within the casing, a perforate spherical shell inclosing the weight and spaced therefrom, said weight being adapted to roll on the raceway as the casing is revolved, and means for revolving the casing.

3. A washing machine including a hollow casing mounted to rotate about an axis and provided with an interior annular raceway, a rolling weight loosely mounted within the casing, a perforate shell surrounding the rolling weight and spaced therefrom, a soft protective covering for the protective shell, the weight and shell being adapted to roll on the raceway as the casing is revolved, and means for rotating the casing.

4. A washing machine including a flattened spherical casing mounted to rotate about its transverse axis, and provided with an interior annular raceway which is substantially semicircular in cross section, a rolling weight loose in the casing, a foraminous spherical shell inclosing the weight and spaced therefrom, a soft perforate outer covering surrounding the foraminous shell, the weight and shell being adapted to roll upon the raceway of the casing when the latter is revolved, and means for rotating the casing.

5. A washing machine including a hollow casing mounted to rotate about an axis and provided with an interior annular raceway, a rolling weight loose within the casing, a foraminous shell surrounding the weight and spaced therefrom, a perforate covering for the foraminous shell, tubular fastening members securing the covering to the shell and extending through the openings of the covering and shell, the weight and shell being adapted to roll on the raceway as the casing is revolved, and means for rotating the casing.

6. A washing machine including a flattened spherical casing mounted to rotate about its transverse axis and provided with an interior annular raceway which is substantially semicircular in cross section, a weight loose in the shell and having short arms projecting therefrom, a perforate spherical shell surrounding the weight in a spaced relation thereto, said shell being

formed in complementary sections which are applied to the weight from opposite sides thereof, fastening members detachably securing the shell to the arms, and means for rotating the casing, the weight and shell 65 rolling in the raceway as the casing turns.

7. A washing machine including a hollow casing mounted to rotate about its axis and provided with an interior annular raceway concentric with the axis, a rolling weight 70 loose within the casing and having short arms projecting therefrom, a perforate shell inclosing the weight and having a spaced relation thereto, said shell being formed in complementary sections which are applied to the weight from opposite sides thereof, fastening members detachably securing the sections of the shell to the arms, a perforate outer covering surrounding the shell, tubular fastening members extending through the 75 corresponding perforations of the covering and shell and holding the cover in position, and means for rotating the casing, the weight and foraminous shell rolling on the raceway as the casing turns.

8. A washing machine including a flattened spherical casing mounted to rotate about its transverse axis and provided with an interior annular raceway concentric with the axis and substantially semicircular in cross section, a spherical weight loose within the casing and having short arms projecting therefrom, a foraminous spherical shell surrounding the weight in a spaced relation and formed in sections which are 80 applied to the weight from opposite sides thereof, the meeting edges of the shell overlapping, fastening means securing the overlapping edges of the shell to the arms of the weight, a perforate protective outer 85 covering for the shell, and means for rotating the casing, the spherical weight and shell rolling on the raceway as the casing revolves.

9. A washing machine including a hollow casing mounted to rotate about an axis and provided with an interior annular raceway, a weight loose within the casing and having foraminous walls, a perforate outer protective covering for the weight, tubular fastening members extending through corresponding openings of the weight and protective covering and securing the covering in position, and means for rotating the casing, the weight rolling on the raceway as the casing 105 revolves.

In testimony whereof I have signed my name to this specification in the presence of two subscribing witnesses.
